Patented Dec. 20, 1921.

Harry C. Adams Inventor

UNITED STATES PATENT OFFICE.

HARRY C. ADAM, OF ST. LOUIS, MISSOURI.

DESIGN FOR A COMBINED WALL-BRACKET AND LAMP.

60,005.

Specification for Design.

Patented Dec. 20, 1921.

Application filed April 15, 1921. Serial No. 461,690. Term of patent 14 years.

To all whom it may concern:

Be it known that I, HARRY C. ADAM, a citizen of the United States, residing at St. Louis, Missouri, have invented a certain new, original, and ornamental Design for a Combined Wall-Bracket and Lamp, of which the following is a specification, reference being had to the accompanying drawing, forming a part thereof.

The figure of the drawing is a perspective view of my new design for a combined wall bracket and lamp.

I claim:

The ornamental design for a combined wall bracket and lamp, as shown.

HARRY C. ADAM.
